UNITED STATES PATENT OFFICE.

CHARLES T. SCHOEN, OF ALLEGHENY, PENNSYLVANIA.

BRAKE-BEAM.

SPECIFICATION forming part of Letters Patent No. 522,032, dated June 26, 1894.

Application filed March 1, 1894. Serial No. 501,948. (No model.)

To all whom it may concern:

Be it known that I, CHARLES T. SCHOEN, a citizen of the United States, residing at Allegheny, in the county of Allegheny and State of Pennsylvania, have invented a certain new and useful Improvement in Brake-Beams, of which the following is a full, clear, and exact description.

The object of this invention is to produce a metal brake-beam of great strength and durability, of very simple and economical construction, and of equal efficiency with those brake-beams heretofore made of metal in a complex manner.

In practicing my invention, I strike up or bend from flat sheet or plate metal, such as soft or mild steel, a laterally flanged double-wedge shaped body, thereby combining in one body the usually separated tension and compression members; shear off the ends so as to present parallel lines to receive the brake-shoe heads, and apply to the center, knee-pieces to receive the brake-lever.

Having thus stated the principle of my invention, I will describe the best mode in which I have contemplated applying that principle and then will particularly point out and distinctly claim the part or improvement which I claim as my invention.

In the accompanying drawings illustrating my invention in the several figures of which like parts are similarly designated, Figure 1 is a plan view; Fig. 2 a rear elevation. Fig. 3 is a section taken in the plane of line 3—3 Figs. 1 and 2. Fig. 4 is a section taken in the plane of line 4—4 Figs. 1 and 2, and Fig. 5 is a section taken in the plane of line 5—5 Figs. 1 and 2.

The body *a* of the beam is formed in any suitable manner from wrought metal, such as sheet or plate soft or mild steel, by means of dies or die-presses, or otherwise. The metal is taken in the form of a rectangular blank, and its longitudinal edges bent at right angles to the body to form flanges *b*, *b'*, and to make a figure resembling in outline a double pointed wedge, truncated at its ends. The outer ends of the flanges are sheared off as at *b* parallel with the surface of the body, and these parallel ends serve to receive the brake-shoe-heads *c*, which latter may be of any ap-

proved form. I have shown these heads applied to the beam by bolts *d*, passed through the flanges *b*, *b'*; and in order to stay the flanges and prevent them from being crushed in, I place hollow stay-posts *e* between the flanges and pass the bolts through them, as clearly shown in Fig. 3.

f, *f'* are eyes riveted to the body to receive the safety chains.

g, *g'* are reversed knee-pieces applied to the body of the beam on opposite sides of an opening *h* therein to receive the brake-lever. The knee-piece *g* is bolted or riveted to the beam between two parallel countersunk ribs *i*, *i*, and the knee-piece *g'* is likewise bolted or riveted to the beam within a pocket *k* pressed up from the bottom of the beam, the walls of the said pocket and the ribs *i*, *i*, serving to take the strain off of the rivets or bolts and prevent the shearing off of their heads. The knee-pieces are provided with holes *l*, *l*, to receive the lever-connecting bolt, not shown. In this construction, the flange *b* would correspond in function with the ordinary compression member and the flange *b'* with the tensile member, and the main body *a* would represent a continuous and unbroken truss or strut between these members. My experience leads me to believe, however, that this solid, one-piece beam is better than a truss-beam, because it is not affected at all by the constant and violent shaking to which a beam is subjected in use, neither is it affected by the torsional and direct strains to which it is subjected. Moreover, the beam may be made with the utmost economy. It is quite as strong as a truss-beam, very much lighter and much less costly.

What I claim is—

1. A brake-beam made of a single piece of metal, of double-ended-wedge-shape and provided with side flanges, substantially as described.

2. A brake-beam made of a single piece of metal, widest at the middle and tapering toward its ends, having edge flanges terminating in lines parallel with the body of the beam and adapted to receive the brake-shoe-heads, substantially as described.

3. A brake-beam of metal having attached knee-pieces to receive the brake-lever, ribs

between which one of such knee-pieces is received, and a pocket within which the other knee-piece is arranged, substantially as described.

5 4. The combination of a brake beam made of a single piece of metal, widest at the middle and tapering toward its ends and having edge flanges terminating in parallel portions, brake - shoe - heads, bolts to unite the shoe

heads and beam and tubular stay-pieces arranged between the parallel flanges and receiving the bolts, substantially as described.

In testimony whereof I have hereunto set my hand this 26th day of February, A. D. 1894.

CHARLES T. SCHOEN.
